(57) **CLAIM**

The ornamental design for a toy gun, as shown and described.

DESCRIPTION

FIG. 1 is a perspective view of a toy gun design showing my new design.

FIG. 2 is a front view of a toy gun.

FIG. 3 is a rear view of a toy gun.

FIG. 4 is a left side view of a toy gun.

FIG. 5 is a right side view of a toy gun.

FIG. 6 is a top view of a toy gun.

FIG. 7 is a bottom view of a toy gun.

FIG. 8 is an enlarged partial view of the toy gun taken from the circle part in FIG. 2.

FIG. 9 is an enlarged partial view of the toy gun taken from the circle part in FIG. 3.

FIG. 10 is an enlarged partial view of the toy gun taken from the circle part in FIG. 6; and,

FIG. 11 is an enlarged partial view of the toy gun taken from the circle part in FIG. 5.

The shade lines shown in the drawings represent the three-dimensional contours of the toy gun and are not intended to indicate surface decoration. The broken line circles in FIGS. 2, 3, 5, 6 and 8-11 are included to show partially enlarged views only and form no part of the claimed design. All other broken lines represent portions of the toy gun that form no part of the claimed design. None of the broken lines form a part of the claim.
